CLAIM

The ornamental design for a battery case for VR headset, as shown and described.

DESCRIPTION

FIG. 1 is a perspective view of a battery case for VR headset showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the battery case for VR headset where the battery case for VR headset is in a first configuration of use;

FIG. 10 is a perspective view of the battery case for VR headset where the battery case for VR headset is in a second configuration of use;

FIG. 11 is a perspective view of the battery case for VR headset where the battery case for VR headset is in a third configuration of use;

FIG. 12 is a perspective view of the battery case for VR headset where the battery case for VR headset is in a fourth configuration of use;

FIG. 13 is a perspective view of the battery case for VR headset where the battery case for VR headset is in a fifth configuration of use; and,

FIG. 14 is a perspective view of the battery case for VR headset where the battery case for VR headset is in a sixth configuration of use.

The broken lines in FIGS. 9-14 depict environment that form no part of the claimed design. The other broken lines in the drawings depict portions of the battery case for VR headset that form no part of the claimed design.

1 Claim, 14 Drawing Sheets
